DESIGN FOR A PICTURE FRAME OR SIMILAR ARTICLE

Milan E. Gabriel, New York, N. Y.

Application June 19, 1944, Serial No. 114,076

Term of patent 7 years

(Cl. D29—20)

To all whom it may concern:

Be it known that I, Milan E. Gabriel, a citizen of the United States, residing at New York, in the county of New York and State of New York, have invented a new, original, and ornamental Design for Picture Frames or Similar Articles, of which the following is a specification, reference being had to the accompanying drawing, forming part thereof.

Fig. 1 is a perspective view of a picture frame showing my new design; and

Fig. 2 is a front elevational view thereof.

I claim:

The ornamental design for a picture frame or similar article, as shown.

MILAN E. GABRIEL,
